DISPENSING PACKAGE FOR INTERFOLDED SHEET MATERIAL

Howard Nelson, Neenah, Wis., assignor to International Cellucotton Products Company, Chicago, Ill., a corporation of Delaware

Application September 16, 1950, Serial No. 185,182

3 Claims. (Cl. 206—57)

1

This invention relates to packaging for interfolded sheet material and particularly to the packaging of fairly large interfolded sheets. Interfolded sheet material such as toilet tissue, paper towels and facial tissue have long been available in packaged form, the packages usually having a base length equally the width of the tissue sheets and a base width equally about one-third or one-half the length of the sheets (depending on the fold of the sheets), the sheets being usually folded either into two approximately equal folds (which form may hereinafter be referred to as "two-fold" material), or into three folds, which form is often referred to as "Z-folded." There are certain other forms of interfolded sheets in which the sheets are folded otherwise than above described but those described probably typify the most common form of interfolded sheet packaging.

The conventional packages referred to have heretofore been provided with dispensing openings to permit withdrawal of the interfolded sheets one by one, each sheet withdrawn being operative to cause withdrawal of a portion of another sheet as an incident to the interfolded relationship of the sheets.

For relatively small sized sheets the described form of packaging is quite satisfactory but when the sheets are of greater width, the packages made in the conventional manner become so long as to be objectionable because of the large table or shelf area required for receiving and supporting the package.

The main objects of the present invention are to provide for interfolded sheet material of relatively large size, dispensing packaging having a relatively small base area to permit the package to be supported on a much smaller shelf or within much smaller table area than conventional packages for the same size of interfolded sheet material; to provide a package of the character indicated which can be easily and economically produced; and in general it is the object of the invention to provide an improved dispensing package for interfolded sheet material.

Other objects and advantages of the invention will be understood by reference to the following specification and accompanying drawing wherein there is illustrated an interfolded sheet package embodying a selected form of the invention.

In the drawings:

Figs. 1, 2 and 3 are more or less schematic illustrations of successive steps in the preparation of the tissue stack for packaging a stack of two-fold interfolded tissue sheets.

2

Fig. 4 is a perspective view illustrating a completed package;

Fig. 5 is a perspective illustrating the package of Fig. 4 opened for sheet dispensing purposes;

Figs. 6, 7 and 8 are diagrammatic representations of the manner in which sheet dispensing progresses sheet by sheet from the improved package of two-fold interfolded sheets.

Figs. 9, 10 and 11 are diagrammatic representations of the manner in which sheet dispensing progresses sheet by sheet from a package of Z-folded interfolded sheets when prepared according to this invention.

In Fig. 1 there is schematically illustrated a more or less conventional stack of two-fold interfolded sheet material such as crepe tissue paper, the stack being disposed in an on-edge position. As shown the stack comprises a first sheet A comprising folds 1 and 2 which are

joined at the top edge of the stack as indicated at 3; a second sheet B having folds 4 and 5 joined at the bottom edge of the stack as indicated at 6, the folds 4 and 5 embracing the fold 2 of the first sheet; and a third sheet C having the folds 7 and 8 joined at the top edge of the stack as indicated at 9, the fold 7 lying face-to-face with the fold 2 and also being embraced between the folds 4 and 5 of the second sheet. Additional sheets are assembled in the interfolded manner indicated to provide the number of sheets desired in the stack.

To prepare this stack of interfolded tissues for packaging according to the present invention, the first fold 1 of the first sheet (at either face of the pack), is unfolded to an upwardly extended position as indicated in Fig. 2, thereby exposing the fold 4 but leaving the first sheet fold 2 in place with the fold 7 between the folds 4 and 5 of the second sheet. From the condition illustrated in Fig. 2 the stack is next folded endwise on itself, i. e., it is doubled upon itself to bring its ends 10 and 11, respectively, together at one side of the folded stack as indicated in Fig. 3. The unfolded or extended fold

1 of the first sheet is of course, also folded upon itself and projects upwardly from the center of the stack. This extended fold or leader portion of the first sheet is flattened down on the top surface of the pack as indicated in Fig. 4 preliminary to or as an incident to insertion of the pack in a container.

A doubled-over stack of interfolded sheet material such as represented in Fig. 3 may be enclosed in a suitable paperboard container 12 such as represented in Figs. 4 and 5. This con-

tainer has a top and bottom or base area suitable to receive the length and width of the top and bottom ends of the folded stack of tissues and the container may advantageously be of such size that the folded stack of sheets will initially be held fairly tightly doubled on itself. However, excess pressure should be avoided in that it may tend to resist withdrawal of the sheets and cause tearing thereof when withdrawal is attempted.

The top wall 13 of the container may be provided with a suitable dispensing opening 14 which may be preformed or which may be provided for in the form of suitable cut-scoring in the top wall along predetermined lines such as indicated at 15 to define a displaceable ear or flap which will leave the required opening 14. This displaceable ear or flap 16 may remain hingedly connected as at 17 to the top wall for which purpose the top wall is creased along the line 17 rather than cut-scored. The opening 14 should be formed in such proportions that it will leave a surrounding portion of the top wall 13 overlying the upper end of the doubled stack of tissues around the extended leader portion 1 when withdrawn through the opening, thereby to prevent the stack from being pulled out of the receptacle as an incident to the withdrawal of a single sheet, especially when the number of sheets remaining in the stack is small and the stack reduced to a very light weight.

If the leader portion 1 of the first sheet is pulled out of the opening 14 and then grasped and pulled upwardly from the pack in the container, frictional engagement existing between the other fold 2 of the first sheet and the folds 4 and 7 on opposite sides of said fold 2 will cause said folds 4 and 7 to follow said fold 2 as it is pulled upwardly approximately as represented in Figs. 6 and 7. When the first sheet embodying the folds 1 and 2 is completely withdrawn, the second sheet B embodying the folds 4 and 5 will be in an unfolded extended position projecting out of the then upwardly projecting fold 7 of the third sheet C, the other fold 8 of said third sheet remaining in place in the interfolded stack. The sheet B embodying the folds 4 and 5 may of course be readily withdrawn from the supporting fold 7 (see Fig. 8) without applying any withdrawing force to the fold 7 since the latter is not confined under any significant pressure against the enclosed fold 5 of the second sheet. When the second sheet embodying the folds 4 and 5 is removed, the remaining upstanding fold 7 will be in exactly the same relationship to the remainder of the interfolded stack as was the first sheet embodying the folds 1 and 2 as shown in Fig. 6. From an inspection of Figs. 6, 7 and 8 and the foregoing explanation, it will be seen that alternate withdrawals from the interfolded stack will start with a projecting sheet portion or leader as represented in Fig. 6 and that the intermediate withdrawals will be of a relatively loosely or freely supported sheet as represented by the sheet A in Fig. 8.

The described arrangement for withdrawing sheets is particularly adapted to the dispensing of fairly rough surfaced sheets which have a considerable amount of face-to-face frictional engagement with one another. Smoother sheets, such as typified by the better grades of soft, smooth facial tissues will be less effectively dispensed by the described arrangement owing to the relatively small amount of friction existing between the sheets, especially when the amount of material left in a package becomes small so

that the compression of the sheets within the package is greatly reduced.

In one practical embodiment of a package of two-fold interfolded industrial wiping tissue (a fairly coarse heavily creped tissue), the sheets measure approximately fifteen inches wide and eleven and one-half inches long and the horizontal or base dimensions of the package are approximately eight inches by four inches as compared with a package size of about six by fifteen and one-half for prior conventional forms of package for the said size of sheet. Hence, it will be seen that the improved package construction will occupy approximately one-third of the area of the prior conventional forms of packaging. The height of the improved package is of course increased considerably over the height of the conventional packages, the new packages being in this instance approximately six and one-half inches high as compared with a depth or height of around two or two and one-half inches for prior conventional packages containing the same number of sheets. This height of the improved packages is far less objectionable than the large base dimensions of the conventional packages so that the herein described construction represents a very desirable and definite improvement over the prior conventional packaging.

In some instances the described dispensing arrangement may be reversed to cause dispensing to take place from the outside of the package rather than from the center thereof. This is of course quite possible as will be readily apparent from an inspection of Figs. 6, 7 and 8 but for most purposes it is preferred that dispensing take place from the center of the package. In that arrangement the outermost sheets in the package serve to protect the main bulk of the package so that in the event that the outermost sheet or sheets become soiled or spotted (for example, by grease or oil when the packages are used around a machine shop or work bench), only the original outer sheets will be damaged.

In Figs. 9, 10 and 11 there is illustrated the dispensing action when the invention is applied to interfolded Z-folded sheets. As shown in Fig. 9, one of the three folds of the central sheet D has one fold or lead portion 18 extended from the top of the pack, the other two folds being indicated at 19 and 20. A second sheet E has a first fold 21 located between the folds 19 and 20 of the sheet D and second and third folds 22 and 23, respectively. A third sheet F has a first fold 24 located between the folds 22 and 23 of the second sheet E. When the first sheet D is pulled upwardly from the pack, the fold 21 of the second sheet E will be incidentally pulled upwardly to the extended position (shown in Fig. 10) which was previously occupied by the fold 18 of the first sheet D. Withdrawal of the sheet E will similarly effect pulling out of the lead or first fold portion 24 of the sheet F. Hence, it will be seen that invention is readily applicable to interfolded Z-folded sheets.

The Z-folded pack represented schematically in Figs. 9 to 11 inclusive should, of course, be enclosed in a suitable container of the character described above.

Various other modifications and changes may be made in the form of the pack and the container while constructing a package employing the main principles of the invention as above described.

I claim:

1. A dispensing package of sheet material

comprising a stack of interfolded sheets, said stack being doubled on itself about an axis paralleling the planes of the folds of the sheets and extending transversely of the fold formed edges thereof, a fold of one of said sheets at a face of the stack being in extended relation to the stack and doubled on itself in conformation with the doubling of the stack as aforesaid, and a container for said stack having a wall portion overlying a side of the folded stack formed by the fold-formed edges of the sheets, said wall portion being provided with a dispensing opening through which said extended fold is readily accessible for facilitating withdrawal of said face sheet from the container substantially as described.

2. A dispensing package of sheet material comprising a stack of interfolded sheets, said stack being doubled on itself about an axis paralleling the planes of the folds of the sheets and extending transversely of the fold-formed edges thereof, a fold of one of said sheets at a face of the stack being in extended relation to the stack and doubled on itself in conformation with the doubling of the stack as aforesaid, and a container for said stack having a displaceable wall portion overlying a side of the folded stack formed by the fold-formed edges of the sheets, said displaceable portion serving upon displacement from the container, to provide a dispensing opening through which said interfolded sheets are withdrawable one by one by movement in a direction substantially normal to the plane of said side of the folded stack substantially as described.

3. A dispensing package of sheet material comprising a stack of interfolded sheets doubled on itself about an axis paralleling the planes of the folds of the sheets and extending transversely of the fold-formed edges thereof, a fold of one of said sheets at a face of the stack being in extended relation to the stack and doubled on itself in conformation with the doubling of the stack as aforesaid, and a container for said stack having a displaceable wall portion overlying a side of the folded stack formed by the fold-formed edges of the sheets, said displaceable portion serving, upon displacement from the container, to provide a dispensing opening therein, said extended fold being initially collapsed on the surface of said side of the pack so as to underlie said displaceable wall portion, whereby said collapsed portion is readily accessible through the dispensing opening provided by displacement of said wall portion, thereby to facilitate withdrawal of said face sheet from the package.

HOWARD NELSON.
